(57) **CLAIM**

The ornamental design for a blender, as shown and described.

DESCRIPTION

FIG. 1 is a top perspective view of a blender, showing the new design;

FIG. 2 is a front elevational view thereof;

FIG. 3 is a rear elevational view thereof;

FIG. 4 is a first side elevational view thereof;

FIG. 5 is a second side elevational view thereof;

FIG. 6 is a top plan view thereof; and,

FIG. 7 is a bottom plan view thereof.

The broken lines shown in the figures depict portions of the blender that form no part of the claimed design.

1 Claim, 7 Drawing Sheets
